[57] CLAIM

The ornamental design for the credenza, as shown and described.

DESCRIPTION

FIG. 1 is a front elevational view of the credenza comprising my new design;

FIG. 2 is a right side elevational view thereof, the opposite side elevational view being a mirror image thereof; and,

FIG. 3 is a top plan view thereof.

The broken lines shown in FIGS. 1 and 2 are for illustrative purposes only and form no part of the claimed design.
